GEAR FINISHING MACHINE

Frederick E. McMullen, Rochester, and Theodore H. Peck, Irondequoit, N. Y., assignors to The Gleason Works, Rochester, N. Y., a corporation of New York

Application August 24, 1951, Serial No. 243,402

13 Claims. (Cl. 51—26)

1

The present invention relates to an improved machine for finishing gears, particularly bevel and hypoid gears, by lapping or burnishing. In general the machine is an improvement upon that disclosed in the L. H. Turner et al. Patent No. 2,445,649, granted July 20, 1948.

In lapping or burnishing (hereinafter for convenience referred to simply as lapping) bevel or hypoid gears according to that patent, the gears are mounted to rotate in mesh on horizontal axes, and while so rotating are moved bodily relative to each other in three mutually perpendicular directions, these being (1) vertically, (2) horizontally along the pinion axis, and (3) horizontally transverse of the pinion axis. The signs and amounts of these motions are so chosen that the gears move relatively between two terminal positions of mesh in one of which the tooth bearing or contact area is at one end of the tooth and in the other of which it is at the opposite end of the tooth. This has the result that during the finishing operation substantially the entire working areas of the teeth are lapped. Between the two terminal positions is the position in which the gears are expected to run in actual use, and for convenience this position will be referred to as the mean position of mesh, although ordinarily it will not be midway between the terminal positions.

In operation of the patented machine one side of the gear teeth is first lapped, and then automatically the direction of rotation of the gears is reversed and the other side of the teeth is lapped. Adjustments are provided on the machine whereby the relative vertical motion of the gears above and below the mean position can be of any desired amount in lapping each side of the teeth. However the horizontal motions are derived by cams from the vertical motion and hence the proportion of the horizontal motions to the vertical motions above and below the mean position must be the same for both sides of the teeth. Thus the resultants of the relative bodily motions (in three directions) of the gears must be in the same directions for lapping both sides although the magnitude of such resultants may be different for the two sides.

It has been found that in most bevel and hypoid gear mountings there is a substantial change in relative position of the gears when the hand of drive through them is reversed, the change referred to being due to clearance in mounting bearings and to like causes, and being additional to positional changes accounted for by deflection of the mountings under load. The change re-

2

ferred to results in there being a different mean position of mesh of the gears when the drive is on one side of the teeth than when it is on the other side. It has also been found that the same proportions of horizontal motions to vertical motions are satisfactory for lapping both sides of the teeth provided that such motions are from two mean positions that are respectively appropriate for the two sides, but such satisfactory results cannot always be obtained when both sides are lapped with the machine adjusted for a single mean position. Where satisfactory results cannot be obtained by automatic operation of the machine, the operator must disable the automatic control mechanism, and, between lapping of the opposite sides, stop the machine and make machine adjustments that will bring the gears to a different mean position of mesh. This of course is not only expensive in terms of time consumed but is likely to be a source of operator error which may lead to spoiled gears.

The present invention provides a set-over mechanism whereby after one side of the teeth has been lapped the gears may be shifted, preferably automatically, to a mean position of mesh suitable for lapping the other side. The set over means preferably includes three pistons, of which there is one for shifting the gears relatively in each of the aforementioned mutually perpendicular directions, and a hydraulic system adapted to operate the pistons simultaneously. Manually operable reversing valve means are provided whereby the directions of motion of pistons may be reversed relative to one another. Also means are provided to adjust the stroke of each piston. By such reversal and stroke adjustments the sign and amount of set-over movement in each of the three mutually perpendicular directions may be determined.

The invention may be applied advantageously to machines having a mechanism for providing a predetermined initial amount of backlash between the gears being lapped, as for example that disclosed in application Serial No. 6,005, filed February 3, 1948, by O. F. Bauer, now Patent No. 2,582,408, granted January 15, 1952. In using this mechanism, the spindle carrying one of the gears is withdrawn (in the direction of the axis of the mating gear) to permit the gears to be chucked. After chucking the spindle is first advanced to bring the gears into metal-to-metal contact, and the mechanism is then actuated to withdraw the spindle by a predetermined amount, thus providing a predetermined amount of backlash. The spindle is then locked in this position.

In the machine of the present invention, the backlash establishing mechanism is preferably applied to the spindle which supports the pinion member of the gear pair being lapped, and the lapping motions (in the three different directions referred to hereinbefore) are applied to the spindle which supports the gear member of the pair. During the lapping of one side of the teeth a certain amount of stock is removed with the result that the backlash becomes greater than that established by the above mentioned mechanism. The set over mechanism of the present invention may be employed to advance the gear, along its axis, to reestablish the original amount of backlash (or to provide whatever other amount of backlash may be wanted) before the other side of the teeth is lapped.

The machine further includes improvements in the system for containing and circulating lapping compound, including means for preventing escape of the compound from the chamber in which the gears are lapped. For the latter purpose a vertically sliding door for the chamber is provided, the door carrying a nozzle for directing compound onto the gears when the door is closed. The compound, in liquid suspension, drains into a sump beneath the chamber, and is pumped from the sump to the nozzle through a flexible conduit. The consistency of the compound is kept uniform by means of an agitator in the sump, but when the machine is not running the solid matter gradually settles. It has been found that if such solid matter is allowed to gather in the pump inlet, it may clog the pump and prevent it from starting. In order to obviate this condition, while at the same time retaining the advantage of connecting the pump inlet to the sump at a level close to the bottom of the sump, the pump inlet passage is arranged to comprise a trap which prevents ingress of the settled material into the pump interior except when the pump is operating.

In addition to the vertically movable door there is an auxiliary gravity closed door hinged on a horizontal axis and serving when closed as the top wall of the chamber. A single hydraulically operated piston is arranged to effect operation of both doors, being connected by a pivoted link to the auxiliary door, and to the vertically movable door by means comprising two racks and intermediate pinions. One rack is carried by the piston, the other by the door, and the pinions are so proportioned that the stroke of the piston is substantially shorter than the travel of the door. The pivoted link which connects the piston to the auxiliary door comprises two parts having a play connection so that lowering of the piston does not necessarily close the auxiliary door, this arrangement being employed as a safety measure.

A means is also provided to prevent operation of the main drive motor of the machine, which rotates the gears being lapped, unless and until the doors are closed. For this purpose a limit switch in the control circuit of the operating motor is arranged to prevent motor operation whenever the piston is away from its door-closed limit position. Means are provided to automatically operate the piston to door-opening position after the main drive motor has stopped at the conclusion of the lapping operation.

This stopping preferably is effected automatically by sequence control means which acts first to stop the supply of lapping compound to the gears, then after a predetermined time lag to

discontinue drive of the gears, and then, after another predetermined time lag, to open the doors. The first time lag preferably is of such duration as to allow compound on the gears to be thrown from them by centrifugal action before their rotation is stopped, and the second lag is preferably sufficient to allow the gears to come to a standstill by the time they become accessible to the operator as a result of opening of the doors.

The foregoing and other objects and advantages of the invention will appear from the following description of the machine shown in the accompanying drawings, wherein:

15 Fig. 1 is a plan view of the whole machine;

Fig. 2 is a fragmentary vertical section taken along line 2—2 of Fig. 1 and shows the piston for setting over horizontally in the direction of the axis of the gear-supporting spindle;

20 Fig. 3 is a vertical section taken as indicated by line 3—3 on Fig. 2, and shows the piston for setting over horizontally in the direction of the axis of the pinion-supporting spindle and also the piston for setting over vertically;

25 Fig. 4 is a fragmentary vertical sectional view taken along line 4—4 of Fig. 2;

Fig. 5 is a vertical section taken as indicated by line 5—5 of Fig. 2, showing the structure in which the gear-supporting spindle is mounted;

30 Fig. 6 is a fragmentary vertical sectional view taken along line 6—6 of Fig. 3;

Fig. 7 is a side elevation of the machine viewed from the direction indicated by 7—7 in Fig. 1, with parts broken away to show the sump for lapping compound and the traps in the passage between the sump and the inlet of the lapping compound;

35 Figs. 8 and 9 are detail vertical sectional views taken respectively along lines 8—8 and 9—9 of Figs. 1 and 8, respectively, and show the door actuating means;

40 Fig. 10 is a detail sectional view taken along line 10—10 of Fig. 9 to show the limit switch switch operated by the door actuating means;

45 Fig. 11 is a diagram indicating one way in which the electrical system of the machine may be wired; and,

Fig. 12 is a diagram of that part of the machine's hydraulic control system with which the invention is concerned.

50 As shown in Fig. 1 the machine includes a bed 21 upon which a drive head 24 is mounted for movement in the horizontal direction indicated by arrow 23. The pinion and gear to be lapped are designated P and G, respectively, the pinion being chucked upon a spindle journaled for rotation in the head 24. The head may be adjusted upon the bed 21 in the direction of arrow 23, by means including handwheel 22; such adjustment being employed to move the pinion horizontally, transversely of its axis, into the desired position of mesh with the gear G. Suitable means controlled by a lever 25 serves to move the head upon the bed, also in the direction of arrow 23, to withdraw the head from such adjusted position for the purpose of chucking and de-chucking the pinion and gear, and to advance the head toward such adjusted position. Final advance of the head, to mesh the pinion with the gear, is effected by manual operation of a jogger valve 26. Backlash of the desired amount between gears P and G may be obtained by manual operation of lever 25 conjointly with operation of levers 27 which control mechanism that retracts the pinion relative to head 24 (also in the direc-

tion of arrow 23) by a given amount after the head has been advanced to bring the gears into metal-to-metal mesh. The mechanism for effecting this backlash setting is essentially as shown in the aforementioned patent application Serial No. 6005.

A column 28 is adjustable horizontally on bed 21 in the direction of arrow 29 by means which include handwheel 30. The spindle upon which the gear G is chucked is journaled (by means hereinafter described in detail) in a head 31 which is movable vertically upon the column. Head 31 is adjustable vertically relative to the column 28 to vary the offset between the axes of the gears P and G, while by the means including handwheels 22 and 30 the gears may be adjusted along their respective axes to whatever mean position of mesh is desired. After the gears have been brought to such position they may be rotated first in one direction and then in the other by a suitable reversible main drive motor that is connected to the pinion spindle, and load may be applied to the gears by suitable braking means 32 or by a generator 40 connected with the gear spindle. While the gears are rotating the head 31 is oscillated through a small amplitude vertically, and simultaneously the gear spindle is oscillated laterally (in the direction of arrow 29) and also axially (the direction of arrow 23) through small amplitudes to effect the lapping over the entire working face of each gear tooth. The lapping compound is directed upon the rotating gears from a nozzle designated 33.

The gear spindle, designated 34, is supported by means which will now be described with reference to Figs. 2, 3, and 5. As shown the spindle is mounted in anti-friction bearings in a housing 35 which is pivotally connected to the head 31 by a pin 36. This mounting enables the lateral oscillatory and set over motions of a spindle 34 which have previously been referred to: While these motions are theoretically arcuate because of the pivotal mounting of the housing, they are of such small amplitude in relation to the center distance between the spindle and pin 36 that for practical purposes they may be considered to be rectilinear.

The housing 35 is supported on pin 36 by a sleeve bearing 37 which enables oscillation of the housing and the spindle, as a unit, in the direction of arrow 23, which, as shown, is axial of the spindle. The head 31 carries two sets of rollers, 38 and 39, which engage upright ways 41 on the column 28 to thereby guide the head for vertical adjustment, and also for vertical oscillating and set over motions. The head also carries rollers 42 which engage an eccentric 43 and are disposed above and below the latter. The eccentric is secured to a horizontal shaft 44 journaled in a bracket 45 which is arranged to slide vertically within the column 28, being guided therein between opposed surfaces 46 on the column. Further guidance is provided by engagement of rollers 47, carried by the bracket, with vertical ways 48 on the column.

The bracket 45 has a nut that is threaded to an adjusting screw 51 whose upper end is supported by the column 28. A graduated dial 52 is secured to the screw, and by turning the screw through a selected angle shown by the graduations on the dial the operator may adjust the bracket up or down by a desired amount. By reason of the eccentric 43 and rollers 42, the head 31 will of course be raised or lowered by the same amount, the eccentric 43 not being rotated while such adjustment is made. By the adjustment the

axes of the gear G and pinion P may be offset as desired.

The means for effecting oscillations of the spindle 34 vertically and horizontally will now be described. Mounted on the bracket 45 is a reversible electric motor 53, hereinafter sometimes called the oscillating motor, which, through a planetary gear high-reduction unit, slowly rotates the shaft 44. This, through operation of eccentric 43 and rollers 42 slowly oscillates the head 31 (and the spindle 34) vertically. The planetary gear reduction unit includes a planet pinion 54 meshing with internal gears 55 and 56 having a small difference in tooth numbers. Gears 55 and 56 are coaxial, gear 55 being fixed to bracket 45 and gear 56 being fixed to a pinion 57. The latter is arranged to drive a gear 58 which is affixed to spindle 44. The planet pinion 54 is carried by a hub that is coaxial with gears 55 and 56; and the hub has integral therewith a gear 59 that is driven by a pinion 61 on the shaft of motor 53. In the particular machine that is illustrated the gearing just described provides an overall reduction from motor to spindle of over 2600 to 1.

The eccentric 43 is oscillated back and forth by motor 53, being rotated thereby for only a fraction of a revolution in one direction, then being rotated for a fraction of a revolution in the other direction, and so on. The amount of motion of the cam to either side of its on-center position (which corresponds to the mean position of mesh of the gears P and G) determines the magnitude of the above-center and below-center vertical motions of the spindle. This amount of motion of the cam is controlled by a reversing switch mechanism, designated 62, which is operated by shaft 44 and serves to control the reversing of motor 53. The mechanism 62 is provided with four independent adjustments by which the vertical movements above and below on-center position can be set independently to whatever values are desired for lapping each of the opposite sides of the gear teeth. The switch mechanism is like that shown in Fig. 8 of the aforementioned Patent 2,445,649 and is not novel with the present invention.

The means whereby vertical oscillation of the head 31 imparts horizontal motion to the spindle 34 in the direction of the pinion axis (the direction of arrow 29) includes a graduated cam 63 mounted for angular adjustment on housing 35. The cam has a plane face 64 engaged by a roller 65. The roller is carried by a cylinder 66 which is mounted to reciprocate upon the rod of a piston 67. The piston rod is pivoted by a pin 68 to an extension of bracket 45, and by a pin 69 is pivoted to a link 71. The latter is pivoted and by a pin 72 to head 31. Assuming the piston and cylinder to be stationary relative to each other (as they are in fact during lapping operation) and the cam face 64 to be adjusted to the inclination shown in Fig. 4, it will be seen from Fig. 3 that as the head 31 moves downwardly relative to bracket 45 (that is as pins 72 and 69 lower relative to pin 68) the roller 65 will be swung upwardly, moving the cam 63, housing 35, and spindle 34, to the right in Figs. 3 and 4 and to the left in Fig. 1 in the direction of the pinion axis (arrow 29). Conversely when the head 31 rises relative to bracket 45 the spindle 34 will be moved in the opposite direction, for the plane cam face 64 is held constantly against the roller 65 by a spring means shown in Fig. 5 which applies a counterclockwise torque to housing 35

about the axis of its pivot pin 36. This spring means comprises a roller 79 that is guided for vertical motion relative to head 31 and is pressed upwardly by a compression spring 80, and a roller 90 that is in contact with the roller 79 and is carried by the spindle housing 35. Also shown in Fig. 5 is a spring-backed locking pin 73 that may be shifted vertically by means of a handle 74 into and out of locking engagement with a recess in the spindle 34. The spindle may thus be locked for the purpose of installing chucking equipment on the spindle, or the like; but of course the lock must be disengaged before the machine is run.

The means whereby vertical oscillation of the head 31 imparts horizontal motion to the gear spindle 34 in the direction of its axis (in the direction of arrow 23) is shown in Figs. 2, 4, and 6. This means includes an upright link 75 pivoted by a pin 76 to the bracket 45 and by a pin 77 to a horizontal lever 78. The latter is pivoted by a pin 79 to an upright lever 81 that is fulcrumed to the head 31 by a pin 82. The upper end of lever 81 is pivotally connected by another pin 83 to the rod of a piston 84 that is arranged for horizontal reciprocation in a cylinder 85 affixed to the head 31. The free end of horizontal lever 78 carries two rollers, designated 86 and 87, which have spherical outer surfaces adapted to contact, respectively, plane cam surfaces 88 and 89 of angularly adjustable cams 91 and 92. The latter have shafts 93 that are mounted for rotation in the spindle housing 34 and have on their outer ends graduated adjusting arms 94 by means of which the machine operator may set the cam surfaces 88 and 89 to whatever inclination is wanted, after he has first loosened the adjacent lock nut 95.

Spring means is provided to urge the housing 35 axially to the right in Fig. 2, to thereby retain the surfaces 88, 89 against the rollers 86, 87. This means comprises a compression spring 96 which acts through a plunger 97 to exert pressure on a horizontal lever 98. The lever is fulcrumed on head 34 by a pin 99 and carries a roller 101 that rides on a guide plate 100 provided on the housing 35.

It will be seen that as the head is moved up and down by the oscillating motor-operated cam 43, the upright link 75, whose lower end is pinned to stationary bracket 45, will swing the horizontal lever 78 up and down about its pivot pin 79. The resulting up and down motion of rollers 86 and 87 will be effective through the cams 91 and 92 to oscillate the housing 35 and the spindle 34 in a direction axial of the spindle (in the direction of arrow 23). During motion of the head 31 above its on-center position the roller 87 coacts with the cam 92 but the travel of the roller 86 is below the cam 91 and hence has no effect. Similarly, during motion of the head 31 below its on-center position the roller 87 and cam 92 are ineffective, but the roller 86 and cam 91 coact. Because of this and the fact that the cams 91 and 92 are adjustable independently, the sign and magnitude of the axial motion of spindle 34 may be adjusted independently for the respective above-center and below center vertical motions of the spindle.

The means for effecting set over betweenlapping the opposite sides of the gears will now be described. Referring to Fig. 3, the screw 51 has a shoulder 102 resting on the upper race of an anti-friction bearing which in turn rests on the lower part of a two-part piston 103. This piston

operates in a cylinder 104 mounted on the column 28 and is keyed against rotation relative to the cylinder. The upper part of the piston is screw threaded to a piston stroke adjusting disc 105 which may be secured to the piston by a set screw 106. The graduated vertical adjustment dial 52 is also secured to the piston, by a set screw 107. While one side of the gears is being lapped the adjusting disc 105 rests on the end plate 108 of the cylinder 104, which bears the weight of the piston 103, the screw 51, the bracket 45 and the bracket supported mechanism including head 31, housing 35 and spindle 34. Before the other side of the gears is lapped hydraulic pressure is applied against the bottom of the piston, elevating the latter until its upper surface abuts against the underside of plate 108, and thereby vertically sets over the bracket 45 (and spindle 34) to another position. It will be understood that the stroke of piston 103 may be varied by loosening the set screw 106 and then turning the adjusting disc 105 upon the screw-threaded upper part of the piston 103. Simultaneously with the vertical set over, transverse horizontal set over of the gear spindle 34 (in the direction of arrow 23) may be effected by reversing hydraulic pressure and return connections to opposite ends of cylinder 66, thereby reflecting movement of the cylinder, and of the roller 65 carried by the cylinder, relative to piston 67. Such motion of the roller is effective through the cam 63 carried by housing 35 to set over the spindle in the direction of arrow 29. The magnitude of this set over may be varied by turning a screw 109 that is threaded into the head of cylinder 66 for abutment with piston 67, to thereby limit the relative motion of the cylinder and piston. As shown in Fig. 3, the screw 109 has a graduated dial to facilitate accurate adjustment, and a set screw is provided to lock screw 109 in adjusted position.

Also simultaneously with the vertical set over, the spindle 34 may be set over axially (in the direction of arrow 23) by reversing the hydraulic pressure and return connections to the opposite ends of cylinder 85, thereby shifting piston 84 and rocking lever 81 about its fulcrum 82, with the result that lever 78 and the rollers 86 and 87 carried by it are shifted in a direction axially of the spindle. Through the effect of the spring 96 and cams 91 and 92 this shifting of the rollers causes axial set over of the housing 35 and of the spindle. The stroke of side set over is adjustable by means of a screw 111, which limits the stroke of piston 84. Like the adjusting screw 109, the screw 111 is provided with a graduated dial and a locking set screw.

During the lapping operation the gears P and G are enclosed in a chamber which has, as one side wall, a vertically disposed door 112 on which the lapping compound nozzle 33 is mounted. The door is arranged to slide vertically on two guide rods 113 (only one of which is shown in Figs. 7, 8, and 9), secured to the machine bed 21 and to a member 114 that is mounted on the fixed wall structure 115 of the chamber. When lowered the door opens to provide access to the gears and to carry the nozzle 33 to a position wherein it can not direct lapping compound onto the gears. The upper wall of the chamber includes an auxiliary door 116 which is hinged to the fixed structure 115 on a horizontal axis, the hinge connection comprising hinge pins 117 secured to the door. As shown the auxiliary door is horizontal when closed, and assumes a nearly upright position

when opened to further provide access to the lapping chamber.

For operating the doors there is provided a hydraulically operated piston 118 vertically movable in a stationary cylinder 119. The lower end of the piston rod constitutes a rack 121 meshing with a pinion 122 that is mounted for rotation upon the fixed structure 115. A larger pinion 123, rotatable as a unit with the pinion 122, meshes with a rack 124 provided on door 112. This arrangement is such that as the piston is raised and lowered between its limit positions, the door 112 is respectively lowered and raised through the much longer travel necessary to open and close it.

The upper end of the piston rod is pivoted at 125 to a connecting rod 126 that in turn is pivoted at 127 to a crank arm 128 keyed to one of the hinge pins 117. As shown, the connecting rod 126 is made of two telescoping sections. Upon upward motion of the piston 118, the crank arm 128 is rotated (clockwise in Fig. 8) as a unit with the auxiliary door 116, opening the latter. Upon downward motion of the piston, the auxiliary door is allowed to lower by gravity, but because of the play connection provided by the telescoping sections of rod 126 the door is not positively closed by down motion of the piston. The play connection thus constitutes a safety means which may prevent possible serious injury to the machine operator should his arm or hand be in the path of the closing door.

The door actuating mechanism controls the normally open two pole limit switch 129, shown in Fig. 10, which is arranged in the electrical control system of the machine. The stem of the switch is moved inwardly, to close the switch, by and upon counterclockwise motion of a pivoted lever 131. The upper end of the lever is engaged and moved counterclockwise by a finger 132 as the latter moves clockwise. The finger is mounted to rotate as a unit with the pinions 122 and 123, and is arranged to close the switch 129 as the doors 112 and 116 reach their closed positions. Light springs 133 serve to hold the lever 131 in its neutral (switch open) position when it is not engaged by finger 132.

Beneath the lapping chamber is a sump 134 for containing the lapping compound, which ordinarily consists of finely divided abrasive material in liquid suspension. To maintain the material well distributed in the liquid during machine operation, there is mounted in the sump an agitator comprising paddle wheels 135 mounted upon a rotatable shaft 136. This shaft is rotated by the main drive motor through suitable drive means within a drive housing 137.

The lapping compound is drawn from the bottom of the sump into the inlet of a pump 138 driven by a motor 139. From the pump outlet the compound is forced through tubing 141 and 142, and nozzle 33 onto the gears P and G. The section 142 of the tubing is flexible to accommodate the opening and closing of the door 112 on which the nozzle 33 is mounted. The nozzle itself is preferably made up of articulated sections in order that the operator may easily aim it to direct the lapping compound on gears P and G of any size that may be placed on the machine. A trap 143, arranged in passage 144 between the sump and the pump inlet, serves to prevent entrance into the pump of abrasive material that may settle out of the lapping compound while the pump motor and the main drive motor of the

machine are not operating, as for example while the machine is standing idle over night.

Suitable seals are provided to prevent the lapping compound from entering the working parts 5 of the machine. For example, bellows-like rubber seals 144 are provided to protect the ways on which the heads 24 and 28 are adjustable, and rubber diaphragms 145 to prevent the compound from passing out of the lapping chamber around the spindles that support the gears P and G.

The hydraulic control system for the set over mechanism will now be described with reference to the hydraulic diagram, and to Figs. 2, 3, and 8. The system includes a sump 151 for hydraulic 15 fluid, a pump 152 operated by a motor 153 for applying the fluid under pressure to the vertical set over cylinder 104 (Fig. 3), the transverse horizontal set over cylinder 66 (Fig. 3), and the axial horizontal set over cylinder 85 (Fig. 2). This 20 application of pressure to the set over cylinders is controlled by an automatically operated solenoid actuated reversing valve 154 and manually set reversing valves 155 and 156. Pressure is also applied from the pump 152 to the door actuating 25 cylinder 119 (Figs. 8 and 9), being controlled automatically by a solenoid actuated reversing valve 157.

The condition shown in Fig. 12 is that solenoid 159 has been energized while solenoid 158 30 has been deenergized (the solenoids being of the repulsion type), so that the valve 154 has been moved to its left limit position and thereby connects pressure line 161 with line 162 and connecting exhaust line 163 (which returns to the sump) 35 with line 164. Lines 162 and 164 communicate respectively with the right and left ends of cylinder 66, so that the latter is retained in its right limit position relative to its stationary piston 67. Valve 155 has been manually moved to the left, 40 and so connects line 162 with a line 165 communicating with the right end of cylinder 85; and also connects line 164 with a line 166 leading to the left end of cylinder 85. Therefore piston 84 is held in its left limit position. Valve 156 45 has also been manually moved to the left, thus connecting line 162 with a line 167 to the bottom of cylinder 104, thus holding the piston 103 in its upper limit position.

When the solenoid 159 is de-energized and solenoid 158 is energized, thereby moving valve 154 to its right limit position; the line 162 is connected, via valve passage 169 with return line 163, and line 164 is connected with pressure line 161. As a result the cylinder 66 will be set over to the 55 left, piston 84 will be set over to the right, and piston 103 will be set over downwardly by the weight of the parts it supports.

By manually shifting valve 155 to its right limit position the connections of lines 162 and 164 60 with lines 165 and 166 are reversed, 162 being brought into communication with 166, and 164 connecting with 165 through valve passage 171. As a result the direction of set over of piston 84 will be reversed relative to that of the cylinder 66. Similarly by manually shifting the valve 156 65 to its right limit position the line 167 is connected through valve passage 172 with line 164, so that the position of set over of piston 103 is reversed with respect to that of cylinder 66.

The valve 157 is brought to the position shown 70 in Fig. 12 by energization of solenoid 174 and de-energization of solenoid 173. In this position pressure line 161 is connected with a line 175 that extends to the lower end of door actuator 75 cylinder 119, and return line 163 is connected

with a line 176 to the upper end of the cylinder. Thus the piston is held in its uppermost position in which the lapping chamber doors 112 and 116 are open. When the valve 157 is shifted to its right position by energization of solenoid 173 and de-energization of solenoid 174, the pressure and return line connections to the cylinder are reversed and the doors are closed. In this latter condition the limit switch 129 is closed as has been explained hereinbefore.

The elements of the electrical control system of the machine are contained largely in a cabinet designated 181 in Fig. 1. The system may be basically like that disclosed in the aforementioned Patent No. 2,445,649 and to avoid needless repetition of the disclosure of the control system, Fig. 11 shows in light lines the identical wiring diagram shown as Fig. 18 of said patent. Connections omitted in the present machine from what is shown in the patent are indicated in Fig. 11 by light dash-dot lines, while the connections and apparatus new with the present disclosure are shown by heavy lines.

As shown in Fig. 11 the solenoids 158 and 159 are connected, between main leads L₁ and L₂ of a three wire source of electricity, in parallel with the reverse and forward windings 182 and 183 of the controller 184 for the main drive motor 185, the connections including a manually operated reversing switch 186. With the position of the switch that is shown, the solenoid 158 is energized simultaneously with coil 182, and solenoid 159 with 183, but by reversal of switch 186 during the set up of the machine, solenoid 158 will be energized simultaneously with coil 183, and solenoid 159 simultaneously with coil 182. This enables reversal of the direction of the transverse horizontal set over (by cylinder 66), relative to the direction of rotation of the main drive motor.

The lapping compound pumping motor 139 has a controller 187 which, when energized connects the motor to the main leads L₁, L₂, and L₃. The coil of the controller is connected in series with start switch button 188 in a circuit between leads L₁ and L₂, so that as soon as the start button is pressed the motor 139 will start. The holding relay 189, which when energized establishes a shunt circuit around the start button, remains energized during the lapping cycle of the machine, and is de-energized at the conclusion of the cycle as a result of the switch arm 191 closing against the contact at station No. 9 of ratchet relay 192.

The door controlling solenoids 173 and 174 are subject to control by relays 193, 194, and 195; and the main motor 185 and the oscillating motor 53 are subject to control by relays 193 and 195 and limit switch 129. The coil of relay 193 is connected in parallel with the coil of holding relay 189 and hence remains energized throughout the lapping cycle. Relay 194 is a time relay primarily for controlling the door, and is of a type which, when energized opens its contact immediately, and when de-energized closes the contact after a predetermined time lag. The relay 195 is also of this general type, and when energized immediately closes its contact 196 and opens its contact 197. When de-energized it closes 197 and opens 196 after a predetermined time delay.

As shown the solenoid 174 is connected across leads L₁ and L₂ in series with contacts of relays 193 and 194, in such manner that it is energized when relay 193 is de-energized and the contact of relay 194 is closed (when relay 194 has been de-energized for a time). Solenoid 173 is con-

nected across leads L₁ and L₂ in series with a contact of relay 193 so as to be energized whenever the latter is energized. The coil of relay 194 is connected across leads L₁ and L₂ in series with contact 196 of the spin time relay 195, and hence is energized when the latter is.

The upper movable contact of limit switch 129 is connected between leads L₁ and L₂ in series with contact 196 of relay 195 and, through a switch arm of relay 199, with a winding of motor controller 184 which are reversed by relay 199. The lower movable contact of limit switch 129 is connected between leads L₁ and L₂ in series with a switch arm of reversing relay 199 and a winding of controller 201 for oscillating motor 53. Controller 201 has forward and reverse windings 203 and 204 which are alternately energized by the relay 199 under the control of the reversing switch mechanism 62. It will be noted that the branch circuits including contact 196 and limit switch 129 replace connections (here designated 202) of the circuit of Patent 2,445,649.

Before a lapping operation is commenced, the gears P and G are mounted and the machine is adjusted to bring them to the desired means position of mesh for lapping one side of their teeth; and the switch 186 and valves 155 and 156 are set, and the strokes of pistons 103, 84, and 67 are adjusted, so that when set over occurs the gears will be brought to the desired means position of mesh for lapping the other side of their teeth. Then the start button 188 is pressed momentarily resulting in the following sequence:

(1) A circuit between lines L₁ and L₂ is established through switch arm 191 of ratchet relay 192 and the right winding of relay 205, closing the right contact of the latter and thereby establishing a circuit which energizes relays 189 and 193. The closing of the left contact of relay 189 establishes a shunt around start button 188 so that release of the latter does not affect operation of the machine. The energization of relay 193 causes solenoid 173 to be energized, thereby shifting valve 157 to the right, causing piston 118 to move down, closing the lapping chamber doors.

(2) Simultaneously with (1) controller 187 is energized starting the lapping compound pump motor 139.

(3) Also simultaneously with (1) the spin time delay relay 195 is energized, immediately closing its contact 196 and opening its contact 197. Closing of 196 energizes door time delay relay 194, immediately opening the latter's contact in the circuit of solenoid 174 (this circuit also being opened at this time by relay 193).

(4) As the lapping chamber doors become fully closed, the limit switch 129 (Figs. 9, 10, and 11) is closed. This establishes a circuit from L₁ to L₂ through the now closed contact 196 of the spin time delay relay 195, the upper contact of limit switch 129, and winding 182 of main drive motor controller 184 (through a contact of relay 199). The main drive motor 185 is thus put into operation. The closing of switch 129 also closes a circuit from L₁ to L₂ through the right contact of relay 198 and the left winding of motor controller 201, thereby putting the oscillating motor 53 into operation.

(5) Simultaneously with (4) i. e. with energization of winding 182, the solenoid 158 is energized with the result that the set over control valve 154 is moved to the right (Fig. 12) causing set over by lowering of piston 103, and movement to the left of piston 84 and cylinder 66.

(6) The lapping operation now proceeds with

functioning of the control systems as described in detail in Patent 2,445,649, the oscillation motor reversing after turning the cam 43 through the desired angle in each direction.

(7) After lapping of one side of the gear teeth has been completed the relay 199 reverses, de-energizing winding 182 and energizing 183 of the motor controller 184. This causes the motor 185 to reverse so that the drive through gears P and G is on other side of their teeth.

(8) Simultaneously with (7) solenoid 158 is de-energized and solenoid 159 is energized, shifting the set over valve 154 to the left and thereby effecting movement of pistons 103 and 84, and of cylinder 66, to the respective positions shown in Fig. 12.

(9) The lapping of the other side of the teeth now proceeds, with the oscillating motor 53 reversing after turning the cam through the desired angle in each direction.

(10) As the foregoing operations take place the switch arm 191 of the ratchet relay 192 is advanced and at the conclusion of lapping is advanced to close the contact at station No. 9. This energizes the left coil of relay 205, thereby de-energizing relays 189, 193, and 195.

(11) The de-energization of the holding relay 189 results immediately in opening of the circuit through the coil of controller 181, so that the lapping compound pump motor is stopped. The de-energization of relay 193 results in door control solenoid 173 being de-energized immediately, but this is without immediate effect since the other door control solenoid 174 is not immediately energized. De-energization of 189 also stops oscillating motor 56.

(12) With a delay after (11) preferably long enough to allow excess lapping compound to be spun off the gears P and G, the contact 196 of relay 195 opens and contact 197 closes. Closing of 197 establishes a circuit from L₁ to L₂ through the now closed right contact of relay 189, left contact of relay 205 and right coil of reversing relay 199, to thereby condition the coil 182 of motor controller for energization on the next lapping cycle. Opening of 196 de-energizes relay 194 but this has no immediate effect.

(13) Simultaneously with (12) the opening of contact 196 of relay 195 breaks the circuit (through limit switch 129) for the winding of motor controller 184, so that the main drive motor 185 is de-energized.

(14) With a delay after (13), preferably long enough to allow the gears P and G to coast to a stop, the contact of relay 194 closes, thereby establishing the circuit through solenoid 174. Valve 157 is thereupon shifted to the left, causing the piston 118 to be elevated and thereby opening the lapping chamber doors so that the now finished gears P and G may be removed.

The foregoing disclosure of the machine and its mode of operation is made by way of example to illustrate and explain the inventive principles involved, and not by way of limitation, for, as those skilled in the art will recognize, various changes and modifications may be made readily without departing from the spirit of the invention or from the scope of the appended claims.

We claim as our invention:

1. A machine having a pair of spindles for mounting gears for running in mesh, relatively movable housings supporting the spindles for rotation, actuating means for moving the housings relatively to each other while the gears are being rotated, means for adjusting the housings where-

by for drive on one side of the gear teeth the motion of the gears effected by the actuating means may be from a mean position of mesh suitable for drive on that side of the teeth, and set over means for simultaneously shifting the housings in different directions whereby for drive on the other side of the teeth the motion of the gears effected by the actuating means may be from another mean position of mesh.

5 2. A machine according to claim 1 in which there is means for adjusting the strokes of the set over means independently in each of said different directions.

3. A machine according to claim 1 in which 15 said plurality of directions are three in number, one housing is supported for movement in each of the three directions, and the operating means and also the set over means act upon only said one housing.

20 4. A machine according to claim 2 in which said plurality of directions are three in number, one housing is supported for movement in each of the three directions, and the operating means and also the set over means act upon only said one housing.

5. A machine according to claim 2 in which the set over means comprises one piston for each of said directions and a hydraulic system for simultaneously shifting the pistons.

30 6. A machine according to claim 3 in which the set over means comprises one piston for each of said directions and a hydraulic system for simultaneously shifting the pistons.

7. A machine according to claim 6 in which the 35 hydraulic system includes means for individually reversing the direction of movement of at least two of the pistons relative to the direction of movement of the other piston.

8. A machine according to claim 1 in which 40 there is a reversible means for driving one spindle to drive the other spindle by meshing engagement of the gears, whereby the drive may be on one side of the gear teeth while the rotating gears are being moved from one mean position of mesh by the actuating means, and then, upon operation of the set over means, the drive may be on the other side of the teeth while the gears are being moved from another mean position of mesh by the actuating means.

9. A machine according to claim 8 in which 45 there is means to effect concomitant reversing of said reversible means and operation of the set over means.

10. A machine having a pair of spindles for 50 mounting gears for running in mesh, a frame, a pair of housings mounted on the frame and respectively supporting the spindles for rotation on horizontal axes, means supporting one housing for vertical motion and also for horizontal motion relative to the frame, actuating means for moving said housing vertically while the gears are rotating, a bracket supporting the actuating means and mounted for vertical motion relative to the frame, means for adjusting said bracket vertically relative to the frame, and means operable by and 55 upon actuating means effected vertical motion of said housing for moving the latter horizontally, the means for moving the housing horizontally including adjustment means for varying the magnitude of the horizontal motion for a given actuating means effected vertical motion thereof, set over means for shifting said bracket vertically between the position to which it has been adjusted and another position, another set over means for shifting said housing horizontally, and means for operating the two set over means simultaneously.

70 75

15

11. A machine according to claim 10 in which the two set over means comprise pistons and said means for operating is an hydraulic system that includes means for reversing the direction of movement of one piston relative to that of the other piston.

5

12. A machine according to claim 10 in which there is reversible means for driving one spindle to drive the other spindle by meshing engagement of the gears, whereby the actuating means effected vertical and horizontal movements of the housing may carry the gears from one mean position of mesh with the drive through them of one hand, and then, upon operation of the two set over means, the vertical and horizontal movements of the housing may carry the gears from another mean position of mesh with the drive through them of opposite hand.

15

16

13. A machine according to claim 12 in which there is means to effect concomitant reversing of said reversible means for driving one spindle and operation of the two set over means.
